United States Patent Office

Des. 178,831
Patented Sept. 25, 1956

178,831

CANDLE

Richard R. Garcia, Laredo, Tex.

Application January 30, 1956, Serial No. 39,959

Term of patent 14 years

(Cl. D73—1)

Fig. 1 is an isometric view of a candle showing my new design;

Fig. 2 is a top plan view thereof;

Fig. 3 is a side elevational view thereof; and

Fig. 4 is an end elevational view thereof.

I claim:

The ornamental design for a candle, substantially as shown.
